WHIRLING BALL THERAPEUTIC AND AMUSEMENT NOVELTY HAT

Bernard D. Herring, 712 Longridge Road,
Oakland, Calif. 94610

Filed Nov. 9, 1973, Ser. No. 414,227

Term of patent 14 years

Int. Cl. D2—03

U.S. Cl. D2—250

FIG. 1

FIG. 2

FIG. 3

FIG. 4

FIG. 1 is a plan view of the whirling ball therapeutic and amusement novelty hat showing my new design;

FIG. 2 is a perspective view thereof with the head strap buckled. The detailed showing of the planets seen in FIG. 1 has been omitted for convenience of illustration.

FIG. 3 is a bottom plan view thereof; and

FIG. 4 is a side elevation thereof.

I claim:

The ornamental design for a whirling ball therapeutic and amusement novelty hat, as shown and described.
